UNITED STATES PATENT OFFICE

PAUL MULTHAUPT, OF DUSSELDORF, GERMANY

MANDREL FOR TUBE ROLLING MILLS

Application filed August 10, 1929, Serial No. 384,916, and in Germany November 26, 1928.

In the production of tubes by rolling, first of all, in the skew rolling mills, the hot ingots are perforated with the help of mandrels, whereon the perforated ingots are then rolled out in the profile rolling mills to seamless tubes likewise with the assistance of mandrels. These mandrels consist of a conical-shaped head, the profile of which at the edge of its base, determines the profile of the rolled 10 tube, and a shank carrying the said head, which shank is attached in the centre on the base of the head. Hitherto the head of the mandrel has been made of highly alloyed special steel or of hard cast iron; in spite of 15 this, these mandrel heads last only a very short time and moreover they allow only comparatively short tubes to be made, since they are subjected not only to high pressures but also to high temperature, so that they wear 20 out with extraordinary rapidity, particularly at their rear sealing edges projecting over the mandrel rod, which is decisive for the profile of the tube.

The invention removes these disadvantages 25 by this, that these mandrel heads or plugs are made of a particular material which does not come into the category of steels, and further that they are given a new shape, so that they are sufficiently resistant to render 30 possible the production in considerable quantities of long tubes by rolling.

According to the invention the mandrels or the mandrel heads are made of tungsten or an alloy containing mostly tungsten. The 35 extraordinary hardness of tungsten carbides is already known; also, it has already been proposed to utilize this property for drawing matrices, for drilling, cutting, turning and similar cold-working tools, by pressing 40 into the desired shape the tungsten or tungsten carbide mixed or alloyed with other substances, after which the shaped articles produced were subjected to a certain heating (up to 1500-1600° C.).

In the present case, however, hot-working 45 tools are under consideration, which have to withstand not only a high temperature but, at the same time, a considerable pressure on all sides.

It has been found in a surprising manner

that tungsten and alloys containing mostly tungsten possess at high temperatures an excellent resistance capability towards deforming forces and a great resistance towards fracture. The present invention depends 55 substantially on the utilization of this new knowledge. The mandrel heads made according to the invention gain in strength with higher temperature, so that a cooling down of the mandrels during the pauses in 60 the work not only is unnecessary, but on the contrary, it is advisable to maintain the mandrel at high temperature. That again means a very much more rapid sequence of 65 passes than is today possible and with it a manifold increase in the working capability of the tube train.

Further the fact already mentioned, that tungsten-carbon alloys are extraordinarily 70 hard, which is to be attributed to the tungsten carbides formed by the alloying, is also utilized. Thus, the mandrel heads made according to the invention last for a period which would be almost unlimited were it not 75 that the ingots and tubes pushed over the heads of the mandrels gradually change the profile by grinding action; however the number of tubes which may be rolled down in rapid sequence on one mandrel head is at 80 least 50 times greater than is today possible with the best-known plug material.

The new mandrels may be made by melting and casting, or, also by sintering. Thus, for example, the material consisting chiefly 85 of tungsten is melted in a particular furnace, the highest attainable temperature being employed, and it flows after complete refining into the mould which is in the furnace, where it solidifies. The moulded article produced in this manner, on account of its great 90 hardness, can be ground to the size suitable for use only by means of diamond dust. Subsequent treatment by forging or jumping is not possible.

The mandrels now in use, forged from 95 steel, or cast from hard cast iron, show at their strongest ends edges which are partly sharp and partly rounded, as is rendered necessary by the manufacturing process or other considerations. Because of the employment 100

of a material which is hard and capable of resistance in every respect, such as in accordance with the present invention, the shape of the most strained part of the mandrel is of decisive importance.

In view of the extraordinary high strain of the mandrel, it is necessary to obtain the new mandrel as a moulded article which, as far as possible, is free from stresses and cavities and without sharp edges which because of the great hardness of the material, must, in consequence of their scraping action, result in the destruction of the cross-section of the tube. The shape of the mandrel head shown in Figs. 1 and 2 of the accompanying drawings shall satisfy these conditions.

According to Fig. 1, the mandrel head *a* seen in front shows the generally usual conical shape down to the sealing edge *b* which determines the profile, which edge is rounded off and passes into a flat conical frustum *c*, to which is attached a plug *d* made of the same material as the head, and extending into the mandrel shank *e* carrying the head.

The modification form shown in Fig. 2 is the same as Fig. 1 with regard to the shape of the head; but, in order to economize in tungsten, a cavity *f* is provided in the mandrel head *a* on the rear side, which serves for the accommodation of a plug made, for example, of iron; this plug projects sufficiently far from the mandrel head in order to be pressed in by means of this free end into a corresponding cavity *g* in the mandrel shank so as to unite the head *a* centrally with the shank *e*.

The connecting plug may, if necessary, also be made in one piece with the mandrel rod, as then in general the union between the mandrel head and the shank may be effected in any other desired manner.

The mandrel head *a* accordingly lies with the surface of the conical frustum *c* on the shank *e* suitably turned out, which embraces it as it were in a suction-like manner in order to produce a uniform distribution of the pressure, whilst the head rounded off in the front part at the place of its greatest diameter projects only a little over the mandrel shank *e* in a small round portion (at *b*), whereby the conical part becomes the seat of pressure within the mandrel shank. This conical frustum *c* contributes to the production of a cast article free from stress and cavities since it forms a transition from the greatest mandrel diameter to the cast-on plug *d*, according to Fig. 1.

What I claim is:—

1. A mandrel for tube-rolling mills comprising in combination with the shank, a head made of tungsten.
2. A mandrel for tube-rolling mills comprising in combination with the shank, a head made of an alloy including a major amount of tungsten.
3. A mandrel for tube-rolling mills com-

prising a head and a shank, said head including a rearwardly extending frustro-conical formation the base of which is of substantially the same diameter as the greatest diameter of the head, the shank having a frustro-conical end cavity, the base of which is of substantially the same diameter as the base of the frustro-conical formation of the head and exactly fitting said formation, whereby the edge portions of the part of the head of greatest diameter are supported by the shank against fracture.

4. A mandrel as set forth in claim 3 in which the shank is provided with a central recess opening into the frustro-conical cavity thereof, and a rearwardly extending plug is provided on the frustro-conical formation of the head extending into said recess.

5. A mandrel as set forth in claim 3 in which the head is provided with a central recess opening through the rear end thereof, and a plug extends forwardly from the shank into said recess.

6. A mandrel as set forth in claim 3 in which the shank is provided with a central recess opening into the frustro-conical cavity thereof, and the head is provided with a central recess opening through the rear end thereof, and a connecting plug extends into both of said recesses.

In testimony whereof I have signed my name to this specification.
